4 Claims. (Cl. 313—104)

This invention relates to electron multipliers.

Electron multipliers for multiplying a beam of electrons by causing the beam to impinge on one or a plurality of secondary electron emitting electrodes are well-known. These multipliers can be operated to obtain a gain of between 10^8 and 10^{10} by employing a suitable number of multiplication stages and whilst in the past various proposals have been made for multiplying an electron image, such attempts have not been satisfactory owing to the difficulty of obtaining a coherent image at the output of the multiplier. The necessity for maintaining the multiplied electron beam in focus throughout the various stages gives rise to such difficulties in maintaining a composite image at the output of the device that no satisfactory practical results in obtaining image multiplication have yet been obtained.

The object of the present invention is to provide an improved electron discharge device with a view to overcoming these difficulties.

A further object of the invention is to provide an electron discharge device having means for generating an electron image, means for projecting said image on to a plurality of secondary electron emitting electrodes such that electrons representing different image points can pass directly from one electrode to the next in separate streams defined by passages in said electrodes so that the definition of the image is preserved throughout the multiplication process.

To obtain adequate definition in the final image derived from the secondary electron emitting electrodes, the cross-sectional area of the passages must be very small in relation to the cross-sectional area of the image on entry into the first secondary electron emitting electrode, since it will be appreciated that the number of image points in the final image is limited to the number of passages in each secondary electron emitting electrode. Therefore in order that this ratio may be decreased when it is not practicable to decrease the cross-sectional area of the passages it is desirable for the cross-sectional area of the electron image to be large and this can be achieved by producing an original electron image of large dimensions, for example by deriving it from a photo-electrically sensitive cathode of large dimensions and employing an optical system for focussing a light image of correspondingly large dimensions on the photo-cathode. This proposal has however, the disadvantage that the mass of the optical lenses required tends to be excessive and therefore according to a preferred feature of the present invention means are provided for magnifying the electron image before said image is projected on the first secondary electron emitting electrode, the secondary electron emitting electrodes being of larger dimensions than the dimensions of the original electron image. Said means for magnifying the electron image may be such as to produce a linear magnification by a factor of about 10 or more.

In order that the said invention may be clearly understood and readily carried into effect, the same will now be more fully described with reference to the accompanying drawings, in which:

Figure 1 illustrates diagrammatically and in sectional view one example of an electron discharge device in accordance with the present invention.

2

Figure 2 is a detailed sectional view of part of Figure 1, the section being taken on the line II—II of Figure 3, and

Figure 3 is a sectional view on the line III—III of Figure 2.

Referring to the drawing, the electron discharge device comprises an evacuated glass envelope 1 having a flat end window 2, on the inner surface of which is deposited a photo-electrically sensitive cathode 3. The device is associated with a lens system represented by the reference 4 for focussing light images on the cathode 3. The envelope has a minimum diameter at the end wall 2 and its diameter increases towards the other end of the envelope and has a maximum in a region 4 in which is mounted a series of secondary electron emitting electrodes, or so-called dynodes. In this example of the invention, the dynodes are twelve in number and are denoted by the references 5₁, 5₂ . . . 5₁₂. The construction of these dynodes will be described in more detail later. The dynodes are generally parallel to the photo-cathode 3 and the effective area of the photo-cathode may be, for example, about 2 inches square, whereas the effective area of each of the dynodes may be 10 inches square. An accelerating electrode 6 which may be in the form of a conductive coating on the inner surface of the envelope 1, is provided for accelerating electrons released from the photo-cathode 2 towards the first dynode 5₁, and an electro-magnet represented by the reference 7 is provided for focussing the electrons from the cathode 3 on to the first dynode in the form of a coherent electron image. The electron optical system formed by the electrode 6 and the electro-magnet 7 is, moreover, such as to produce a magnification of the electron image focussed on the first dynode 5₁ by a factor equal to the ratio of the effective dimension of the dynode 5₁ to that of the photo-cathode 3. The magnification factor in the present example is of the order of 5. As will hereinafter appear, the electron image focussed on the first dynode 5₁ undergoes successive stages of multiplication in the series of dynodes 5₁ . . . 5₁₂ and the electrons from the last dynode 5₁₂ are projected directly on to a fluorescent screen denoted by the reference 8, the fluorescent screen being deposited on a conductive but substantially transparent layer provided on, or constituting, a transparent support for the fluorescent screen. Leads from the various electrodes project to the exterior of the envelope 1 and for operation of the device the photo-cathode 3 may, for example, be grounded and a potential of 500 volts applied to the accelerating electrode 6. Moreover, successively higher potentials in the range from 500 to 1,500 volts are applied to the successive dynodes 5₁ . . . 5₁₂, means for applying such potentials being represented in the drawing as a potentiometer 10 connected across a suitable potential source. Moreover, a potential in the range from 5,000 to 10,000 volts is applied to the conductive support for the fluorescent screen 8.

In Figures 2 and 3 the construction of two of the dynodes is illustrated and it will be assumed that these dynodes are the dynodes 5₁ and 5₂. Each dynode is of the so-called Venetian blind type and comprises an array of substantially parallel slats 11 which are inclined to the path of the electrons, the angle of inclination being, for example, 45° to the general direction of motion of the electron stream in the device and the slats 11 of alternate dynodes being oppositely inclined. The spacing of the slats is, moreover, such that they intercept practically all electrons which enter from the photo-cathode or from the previous dynode. A fine pitch low-shadow-ratio mesh 12 is extended in front of each dynode to prevent the suppression of secondary electrons liberated from the respective dynode by penetration of the relatively negative electrical field from the previous dynode or elec-

trode. The mesh 12 is carried on vertical extensions 13 which project forwardly from the inclined portions of the slats 11. This has the effect of allowing better penetration of the electrical field from each dynode (other than the first) into the preceding dynode so as to facilitate the extraction of secondary electrons liberated at the front edge of the preceding dynode. Each dynode comprises a further array of parallel ribs also in the form of slats perpendicular to the array of slats 11. A few of these ribs are represented by the reference 14 and they serve as stiffening members to provide accurate spacing of the slats 11 and in conjunction with the slats they partition each dynode into a two dimensional array of box-like passages which prevent secondary electrons spreading along the direction of the slats 11. The ribs 14 and the slats 11 produce focussing fields which steer the secondary electrons representing different image points directly from one dynode to the next in separate streams, in such a way that the electrons representing each image point when they emerge from the final dynode 5₁₂ are discrete and not associated with electrons which have been derived from other image points. To facilitate the isolation of the streams the dynodes are mounted as close to one another as possible and the individual passages formed by the intersecting slats and ribs in the successive dynodes are aligned as accurately as possible as represented for the case of the dynodes 5₁ and 5₂ in Figures 2 and 3 so that the exits from the passages in one dynode register with the entrances to the corresponding passages in the next dynode. The ribs 14 do not extend throughout the whole depth of the slats 11, to prevent excessive screening of the extracting electrical field.

Furthermore, the cross-section of the passages formed by the slats and ribs are arranged to be very small so as to provide for a very large number of image points and thereby ensure high definition. For example, with dynodes having the overall dimensions above indicated there may be one hundred slats and one hundred ribs, providing 10⁴ elemental electron multipliers in each dynode and thus 10⁴ picture points, corresponding to an image having one hundred lines. The cross-section of each elemental electron multiplier is then 0.1" x 0.1". The fluorescent screen 8 is mounted close to the last dynode as shown and produces a bright display of the original optical image focussed on the photo-cathode 3 with a definition corresponding to the number of elemental electron multipliers. The above dimensions are given by way of example and it will be understood that the number of slats and ribs may be greater, and the dynodes may be of larger overall size.

Instead of projecting the final electron image from the dynode 5₁₂ on a fluorescent screen, it may be projected on a target electrode of the charge storage type such as used, for example, in conventional television pick-up tubes. Picture signals representative of the original light image can then be derived from this target by scanning it with a beam of electrons, preferably of low velocity. Alternatively, where a fluorescent screen such as 8 is provided, picture signals may be derived from it by utilising a conventional television pick-up tube to pick-up the light image directly from the fluorescent screen. The device may also find application in colour television to give successive pictures in red, blue and green which are directed by shutters sequentially into three pick-up tubes from which picture signals are derived by conventional scanning.

The discharge device in accordance with the invention can be utilised not only as part of or in conjunction with a television pick-up tube, but it can also be used for direct visual observation, for example in astronomy or as an aid to vision at night or in conditions of poor visibility. The device can also be used in photography, for example for making time exposures of images such as faint spectra. Furthermore, if the photo-cathode 3 is formed in close juxtaposition to an X-ray sensitive fluorescent screen, the

device could be employed for X-ray image intensification. Alternatively, the device in the form shown could be used for direct observation of an X-ray fluorescent screen as now used. On the other hand, the device can be used as an ultra-violet light microscope by making the end wall 2 in the form of a quartz window.

What I claim is:

1. An electron discharge device comprising means for generating an electron image, a plurality of secondary electron emitting electrodes, means for projecting said image along a path onto the first of said electrodes, each said electrode comprising a first array of parallel slats, said array being parallel to said image, and said slats being inclined to said path of said image, and a second array of parallel ribs, transverse to said first array with the ribs intersecting the slats, so that the slats and ribs of said first and second arrays define a two dimensional array of passages oblique to said path, in which said electrodes are arranged adjacent one another and are disposed so that the exit of each passage in each electrode is in alignment with the entrance of a single passage in the next electrode, so that electrons representing different image points can pass directly from one electrode to the next in separate streams defined by said passages, and a target arranged for exposure to the individual electron streams from the last secondary electron emitting electrode.
2. An electron discharge device comprising means for generating an electron image, a plurality of secondary electron emitting electrodes, means for projecting said image along a path onto the first of said electrodes, each said electrode comprising a first array of parallel slats, said array being parallel to said image, and said slats being inclined to said path of said image, and a second array of parallel ribs transverse to said first array with the ribs intersecting the slats, so that the slats and ribs of said first and second arrays define a two dimensional array of passages oblique to said path, and a mesh extended in front of each electrode to prevent the suppression of secondary electrons liberated from the respective electrode, in which said electrodes are arranged adjacent one another and are disposed so that the exit of each passage in each electrode is in alignment with the entrance of a single passage in the next electrode, so that electrons representing different image points can pass directly from one electrode to the next in separate streams defined by said passages, and a target arranged for exposure to the individual electron streams from the last secondary electron emitting electrode.

3. An electron discharge device according to claim 1 in which said means for projecting said electron image along a path onto the first of said secondary electron emitting electrodes comprises means for magnifying said electron image.

4. An electron discharge device according to claim 2 in which said means for projecting said electron image along a path onto the first of said secondary electron emitting electrodes comprises means for magnifying said electron image.
